Everett Rock,

ATTORNEYS.

UNITED STATES PATENT OFFICE.

JOHN L. SOMMER, OF NEWARK, NEW JERSEY, ASSIGNOR TO J. L. SOMMER MANUFACTURING CO., A CORPORATION OF NEW JERSEY.

KEY-RING CLIP.

1,392,715.

Specification of Letters Patent.

Patented Oct. 4, 1921.

Application filed July 23, 1921. Serial No. 486,938.

To all whom it may concern:

Be it known that I, JOHN L. SOMMER, a citizen of the United States, and a resident of Newark, in the county of Essex and State 5 of New Jersey, have invented new and useful Improvements in Key-Ring Clips, of which the following is a specification.

This invention relates to that class of clips which are commonly used for securing 10 a bunch of keys to one's belt, at the hip, and the objects of the invention are to secure an improved construction of such clips and one which shall hold the key ring more securely; to thus prevent the keys from escaping and 15 being lost; to obtain for this purpose an engagement of the spring tongues with the body portion which the key-ring is unlikely to pass; to still have the body portion fit and coöperate with both spring tongues; 20 to enable the clip to be easily operated, and to obtain other results and advantages as may be brought out by the following description.

Referring to the accompanying drawings, 25 in which like numerals of reference indicate the same parts throughout the several views,

Figure 1 is a perspective view of my improved clip in use;

Fig. 2 is an edge view of the same, and 30 Fig. 3 is a front or face view.

In said drawings, the body portion of my improved clip is shown having end portions 1, 2 which are preferably flat and straight, lying in substantially parallel planes as 35 shown in Fig. 2. These end portions are connected by an ogee-curved middle portion, 3, 4, and at their outer ends the strip-like material of which the clip is formed is bent or looped as at 5, 5 and returned at the side 40 of each end portion away from the plane of the other end portion, forming spring tongues 6, 7. These tongues lie at their ends against the opposite sides of the ogee-curved middle portion 3, 4, of the body 45 part, and are curved similar thereto so as to fit against the same, as shown at 8, 9, and 10, 11 in the drawing. The extremities, 12 and 13, of the spring tongues project or curve away from the adjacent end portions 1 and 50 2 of the body portion of the clip, so as to

afford an easy starting of the key-ring in applying it.

It will be understood that the ogee-curved middle portion 3, 4 of the body portion of the clip coöperates with both of the similarly curved ends of the spring tongues 6, 7, its opposite sides forming seats against which they both fit closely. Obviously the resistance to the passage of a key-ring 14 through either of the sinuous closures thus 55 formed is considerable, and there is no danger of the keys being inadvertently lost; at the same time the construction is compact, and it can readily be applied to a belt 15, as shown.

While I prefer to employ the ogee bends which I have shown and described, it is within the spirit and scope of my invention to use other forms of bends, so long as they are such that the middle body portion co- 70 operates with both of the spring tongues in the manner described; that is to say, its bending to form a sinuous passage with one of the spring tongues forms also a similar passage with the other member.

Having thus described the invention, what 75 I claim is:

1. A key ring clip having a body portion and spring tongues returned from the ends of the body portion on opposite sides thereof 80 and extending each past the free end of the other, the three overlapping portions being bent as a unit to form tortuous passageways.

2. A key ring clip having a body portion and spring tongues returned from the ends 85 of the body portion on opposite sides thereof and extending each past the free end of the other, the three overlapping portions being bent sinuously as a unit to form tortuous passageways.

3. A key ring clip having a body portion and spring tongues returned from the ends 90 of the body portion on opposite sides thereof and extending each past the free end of the other, the three overlapping portions being bent as a unit to form similar tortuous entrances beneath the two tongues.

4. A key ring clip having a body portion and spring tongues returned from the ends 95 of the body portion on opposite sides thereof 100

and extending each past the free end of the other, the three overlapping portions being bent first in one direction and then in the other so as to bring the end portions of the 5 body portion in substantially parallel spaced planes.

5. A key ring clip having a body portion

and spring tongues returned from the ends of the body portion on opposite sides thereof and extending each past the free end of the other, the three overlapping portions being bent on an ogee curve at the middle of the 10 length thereof.

JOHN L. SOMMER.
